CONTROL SYSTEM FOR HEATERS

William J. Masoner, Oak Park, Ill.

Application May 3, 1934, Serial No. 723,695

1 Claim. (Cl. 126—110)

Heating of shops, stores, offices, and the like, is now often accomplished by means of gas fired heater units which are individually controlled by thermostats and by individual switches. 5 Each unit has an electric fan which circulates air therethrough, the fan being automatically driven during the time gas is being burned in the heater, and being cut off at the same time the gas is shut off from the heater unit. It is 10 desirable to use these same fans for circulating air during summer months.

An object of this invention is to provide a means for readily driving the fan independently of the heater unit, and to control this means by 15 the valve which shuts off the flow of gas to the heaters.

Another object is to provide a combination interconnected gas shut-off valve and electric switch for the above purpose.

20 Another object is to provide in a gas furnace or heater, a combination of shut-off valve and control valve, the latter being controlled by the former as well as by the gas pilot so that the control valve will not open if the furnace pilot light is out.

These and other objects, as will hereinafter appear, are accomplished by this invention which is fully described in the following specification and shown in the accompanying drawings, in 30 which—

Figure 1 is a side elevation partly in section of a gas heater unit showing the gas cock switch applied thereto;

Fig. 2 is an enlarged horizontal section on the 35 line 2 of Fig. 1 showing the combination of the gas cock and electric switch operable by the rotatable plug of the cock;

Fig. 3 is a transverse section through the gas cock and switch on the line 3 of Fig. 2;

Fig. 4 is a vertical section on the line 4 of Fig. 3;

Fig. 5 is a wiring diagram of the heater unit and the gas cock switch.

The embodiment shown in Figs. 1 to 5, inclusive, comprises a gas heater unit A with a gas cock switch B applied thereto, as will later be described in detail. The gas heater unit A in itself forms no part of the present invention, and comprises a series of vertical tubes 10 which are heated by any suitable combustible gas supplied to a burner 11 through pipes 12, 13 from a suitable source of gas supply, not shown. The hot gases from the burner 11 pass up through the tubes 10 and out through a suitable pipe 14 55 to a stack, not shown.

An electric motor 15 drives a fan 16 which serves to pass air of the room to be heated over the hot tubes 10, thereby effecting a transfer of heat. The air issuing from the heater unit is directed by means of vanes 17. Brackets 18 serve to support the heater unit in any convenient position in the room. Gas from the main 13 passes through a suitable reducing valve 19, and thence through the gas cock B which is part of the present invention.

This gas cock and switch is shown in detail in Figs. 2 to 4 inclusive, and comprises a cast body 20 in which is rotatably mounted a tapered plug 21 operable by means of a handle 22, and carrying a pin 23 which encounter stops 24 on the body which, however, permit a 90° oscillatory movement of the plug which has the usual opening 25 therethrough. The plug cock prevents the passage of gas when turned in the position shown in Fig. 3, and permits the free passage of gas therethrough when turned at right angles to the position of Fig. 3 to the dotted line position of Fig. 2.

The plug 21 carries a finger 26 which is rotatable therewith to engage a forked lever 27 on a toggle switch 28 of a well known type. This switch, which need not be described in detail as it forms no part of the present invention, comprises a metal roller 29 which is adapted to be rolled back and forth on an arcuate track 30 as the lever 27 is moved from the full line position to the dotted line position, or vice versa, of Fig. 4. This roller when in the full line position of Fig. 4 engages a switch contact 31 on the near side of Fig. 4, and a similar contact member 32 on the far side as shown in Fig. 3, thereby closing the switch. As the lever 27 is moved toward the dotted line position the roller 29 is suddenly snapped to the opposite end of the track 30, thereby opening the switch.

The switch 28 is mounted within a housing 33 secured to the body of the cock by means of screws 34, and has a cover 35 secured thereon by screws 36. Within this housing is mounted a switch 37 preferably of the type known as a "snap" switch which is operated by means of a pull chain 38.

Referring now to the wiring diagram of Fig. 5, the motor 15 which may be of any suitable type is connected at one side through a lead 39 to a line 40 which is connected to a suitable source of electric current. The opposite side of the motor connects through a lead 41 with the switch 28, and this is connected in series with the switch 37, and this in turn connects through

a lead 42 with the opposite side of the line 40. With both the switches 28 and 37 closed, the motor will be driven by current from the line and in turn will drive the fan 16. The switch 5 28, however, will be closed only when the plug cock is closed, as previously described.

In normal operation of the heating device the plug cock will be open, at which time the switch 28 will be in the dotted line position of Fig. 4, 10 and will be open as shown in Fig. 5. At such a time it will be immaterial whether the switch 37 is open or closed, as it will be rendered inoperative due to the fact that the switch 28 is open. At such a time the motor is supplied by 15 electric current from the lead 39 as before and through a lead 43, through a cutout switch 44 which is normally maintained closed by heat from the gas pilot of the heater unit, thence through a lead 45, through a manually operable 20 switch 46, thence through a room thermostatic switch 47, and back through a lead 48 to the line 40.

Thus with the switch 46 normally closed and with the cutout switch 44 held closed by heat 25 from the gas pilot, the room thermostatic switch 47 opens and closes, and as it does so it stops and starts the motor 15. This motor in turn controls through a governor, not shown, a gas valve 49 (Fig. 1) so that this gas valve opens 30 when the motor is in operation, thereby supplying gas to the heater at the same time the fan is operated, and shutting off gas to the heater unit when the fan is stopped. This also forms no part of the present invention, and 35 accordingly is not illustrated.

Thus it will be seen that with the gas heater unit A in operation in the usual way the gas

cock 25 is turned to the full open position, during which time the switch 28 is open. When, however, it is desired to operate the fan 16 without using the heater unit the plug cock 25 is turned to the full line position of Fig. 2, 5 at which time the gas is shut off from the heater by the gas cock, and at the same time the switch 28 is closed. At that time the fan is then controlled entirely by means of the switch 37.

While I have shown and described but a few 10 embodiments of my invention, it is capable of many modifications. Changes, therefore, may be made which do not depart from the spirit and scope of the invention as disclosed in the appended claim.

I claim:

The combination with a heating unit including a fan, a heater for heating air delivered by the fan, said heater including a fluid fuel burner, and means including a first electric circuit controlling said fan and burner in response to room temperature, of a main valve controlling fluid fuel delivered to said burner, a first switch operated to open and closed positions by the opening and closing of said valve, a second switch 20 connected in series with said first switch and being manually controlled, and a second control circuit connecting said fan and switches whereby when said valve is open the second control circuit is opened to enable complete 25 control of the fan and burner by the first circuit and when said valve is closed to enable complete control of said fan by said manually operable switch when said first circuit is deenergized.

WILLIAM J. MASONER.
